TOILET TANK OUTLET FITTING AND
ELBOW

Jesse C. Owens, Los Angeles, Calif.

Application November 4, 1942, Serial No. 464,483

3 Claims. (Cl. 4—57)

My invention relates to an elbow and outlet fitting for toilet flush tanks and has for its principal objects, to generally improve upon and simplify the construction of the conventional toilet tank elbows and fittings, to construct the elbow and fitting from non-rusting, non-corrodible material such as plastics, and further, to provide the elbow with simple means for imparting whirling motion to the water that discharges through said elbow, thereby accelerating the flushing function and at the same time tending materially to decrease the hissing and gurgling noises which usually attend the flow of water from the tank to the toilet bowl.

A further object of my invention is, to provide a simple and effective means for guiding the ball valve during its movements toward and away from its seat, such guiding means projecting from the upper end of the elbow, upwardly through the water discharge opening in the fitting and which arrangement eliminates the necessity for providing means anchored on the overflow tube or wall of the tank, for guiding the ball valve and the rod or stem carrying same.

With the foregoing and other objects in view, my invention consists in certain novel features of construction and arrangement of parts that will be hereinafter more fully described and claimed and illustrated in the accompanying drawing in which:

Fig. 1 is a section taken vertically through the center of my improved elbow and fitting.

Fig. 2 is a horizontal section taken on the line 2—2 of Fig. 1.

Fig. 3 is a perspective view of the member that is positioned in the upper end of the elbow and which serves to impart whirling motion to the water entering the elbow, also as the guide for ball valve.

Fig. 4 is a detail section taken on the line 4—4 of Fig. 1.

Referring by numerals to the accompanying drawing, which illustrates a practical embodiment of my invention, 10 designates the bottom of a toilet flush tank and 11, the opening formed in the bottom of the tank for the reception of the outlet fitting.

The fitting, in order to decrease manufacturing costs and facilitate production is preferably molded in two parts, upper and lower and with the joint between said parts disposed in a horizontal plane.

The lower part includes a ring-shaped body 12, from which depends a short tubular member 13, the same projecting through opening 11 in the

bottom of the tank. This tubular member may be externally threaded for the reception of a nut 14, or when the fitting is formed from plastic material, an externally threaded metal sleeve 15 is mounted on member 13, with the upper end of said sleeve embedded in ring 12.

A packing ring or gasket 16 is positioned between ring 12 and the upper face of the tank bottom 10 around the opening 11, thus effectively sealing the joint between the tank and member 13 when nut 14 is tightened against the underface of said bottom.

Formed integral with the upper portion of ring 12 is a short horizontally disposed arm 17 having a shallow recess 18 in its upper face, said recess communicating with the opening through said ring.

The upper members of the fitting includes a ring-shaped member 19 which fits directly upon the upper face of ring 12 and projecting from the lower portion of said member 17 is a short horizontally disposed arm 20 which registers with and overlies arm 17.

The outer end of arm 20 terminates in a vertically disposed collar 21, in which is seated the lower end of a conventional toilet tank overflow tube 22.

The underface of arm 17 is recessed so as to register with the recess 18 in arm 17.

30 The upper edge of ring 19 is chamfered to provide a seat 23 for a ball valve 24, preferably of rubber and which controls the discharge of flushing water from the tank into the elbow.

Ball valve 24 is mounted on the lower end of a rod or stem 26 that is lifted by the trip lever of the tank and formed in the lower end of said valve is an aperture 27 surrounded by a rib 28.

Positioned in the lower portion of tubular 13 is the upper end of a tubular elbow 29 and arranged on top of the upper end of said elbow within tubular member is a ring 30, and secured within same is the upper end of a spiral deflector 31, of thin material which makes at least, one complete turn.

45 Suitably secured to the center of the upper edge of deflector 31 is the lower end of an upwardly projecting finger 32, preferably composed of three thin webs disposed 120 degrees apart.

This finger which gradually tapers toward its upper end projects upwardly through aperture 27 into ball valve 24, and a small cross arm 29 on the upper end of said finger provides a stop to limit the upward movement of the ball valve.

Finger 32 serves as a guide for the ball valve during its vertical movements and as said valve

is formed of rubber or like flexible material having a certain degree of resilience, the size of opening 27 may be increased by stretching the adjacent rubber to such a degree as to permit cross bar 33 to pass through said opening.

Seated in the lower end of elbow 29 is a spiral deflector 33 similar to deflector 31 and thus the water passing from the lower end of the elbow is caused to whirl, thereby increasing the flow of said water and at the same time materially decreasing the noise of flow.

When the toilet tank trip lever is actuated to raise ball valve 24 from its seat the finger 32 serves to guide said valve and after the water has discharged from the tank, the finger guides the ball on the return to its seat.

The spiral deflectors 31 and 33 impart whirling motion to the water entering and discharging from the elbow and which action exerts a pull on the water within the tank so as to bring about a quick discharge of said water and tends to silence the flow thereof.

Thus it will be seen that I have provided an outlet fitting and elbow for toilet flush tanks that is simple, strong and durable in structure, inexpensive of manufacture and very effective in performing the functions for which it is intended.

It will be understood that minor changes in the size, form and construction of the various parts of my improved outlet fitting and elbow may be made and substituted for those herein shown and described without departing from the spirit

of the invention, the scope of which is set forth in the appended claims.

I claim as my invention:

1. In a toilet tank outlet fitting and elbow, the combination with a tank, of an outlet fitting in the bottom of said tank, said fitting provided with a valve seat, a valve normally resting upon said seat, an elbow connected to said fitting below said valve seat, a ring seated in said fitting above the upper end of said elbow, a spiral deflector secured to said ring and a valve guiding member projecting upwardly from said deflector through said valve seat.

2. The combination as set forth in claim 1, said valve being hollow and provided in its lower end with an aperture for the accommodation of said valve guiding member and a stop on the upper end of said guiding member for limiting the upward movement of said valve.

3. The combination with a toilet tank, of an outlet fitting therefor, a valve seat on the upper end of said fitting, a hollow valve adapted to rest on said seat and cut off flow of water through said fitting, there being an opening in the bottom of said valve, a spiral deflector fixed within the upper portion of said outlet fitting for imparting whirling motion to the water entering and passing through said fitting and a valve guide projecting upward from said deflector and through the opening in the bottom of said valve.

30
